UNITED STATES PATENT OFFICE.

EDWIN LUNT, OF NEWBURYPORT, MASSACHUSETTS.

SHOE.

SPECIFICATION forming part of Letters Patent No. 340,052, dated April 13, 1886.

Application filed November 30, 1885. Serial No. 184,267. (No model.)

To all whom it may concern:

Be it known that I, EDWIN LUNT, of Newburyport, in the county of Essex, of the Commonwealth of Massachusetts, have invented a new and useful Improvement in the Manufacture of Shoes; and I do hereby declare the same to be described in the following specification and represented in the accompanying drawings, of which—

10 Figure 1 is a side view, Fig. 2 a top view, Fig. 3 a transverse section, and Fig. 4 a bottom view, of a cloth slipper made in accordance with my invention, the nature of which is defined in the claim hereinafter presented.

15 In the said drawings, A denotes the shoe-upper, usually of cloth. B is the main sole, usually of felt; C, an outer or protection sole, usually of vulcanized rubber, while D is the cloth lining, including the insole a, which is 20 integral with or connected to the lining.

After the upper has had the lining placed within it and connected to it at the edges of the mouth of the shoe by binding b, lapped upon and stitched to them, the upper is to be lasted, the main or felt sole is to be placed within the upper and against the insole a, after which the outer or protection sole is to be placed on the main or felt sole, and with it pinned or nailed to the last. This having 25 been done, the upper, the felt sole, and the protection-sole are to be connected by a line or range of stitches going through them parallel with and at a short distance within the edge of each, the projecting edge of the upper 30 being subsequently suitably trimmed, if necessary.

The upper is composed of the vamp d and quarters e e, as in most other shoes.

In Figs. 3 and 4 the stitching is shown at c. The stitching does not go through the lining, either in the portion thereof within the vamp or through the insole making part of the lining. By having the lining of the vamp connected to the insole or integral therewith there is saved the necessity of fastening the lining 45 by sewing it with the vamp to the outer sole or soles, and thereby increasing the thickness of the material or vamp fixed thereto. I usually cement the insole part of the lining to the outer sole. 50

I do not claim a shoe made as represented in either of the United States Patents Nos. 295,973 and 301,816, neither having to it any lining in which the insole forms a part, as is the case in my shoe. 55

I claim—

As a new or improved article of manufacture, a shoe or cloth slipper composed of an upper or vamp and quarters and two outer soles lapped together and combined with and by a row of stitches extending through and about them near their edges, and of a lining arranged within the upper and including an insole, and connected to the upper at the mouth thereof by a binding stitched to both 60 lining and upper, all being substantially as set forth, such insole being integral with or connected to the portion of the lining extending from it without being stitched to the outer sole and the vamp. 65

EDWIN LUNT.
